UNITED STATES PATENT OFFICE

173,157

LIGHTING FIXTURE LOUVER

Raymond F. Hurley, Marinette Park, Ill.

Application March 26, 1954, Serial No. 29,704

Term of patent 14 years

(Cl. D48—23)

To all whom it may concern:

Be it known that I, Raymond F. Hurley, a citizen of the United States, residing at 11725 Sacramento Avenue, Marinette Park, Illinois, have invented a new, original, and ornamental Design for a Lighting Fixture Louver, of which the following is a specification, reference being had to the accompanying drawing, forming a part hereof, in which—

Figure 1 is a bottom perspective view of a lighting fixture louver, showing my new design;

Figure 2 is a bottom plan view thereof, and

Figure 3 is a side elevational view partly broken away and in section.

I claim:

The ornamental design for a lighting fixture louver as shown.
